US00D794372S

(12) **United States Design Patent** (10) **Patent No.:** **US D794,372 S**
(45) **Date of Patent:** **** Aug. 15, 2017**

(54) **COLLAPSIBLE CHAIR FRAME**

(71) Applicant: **Zhuhai Shichang Metals, Ltd.**, Zhuhai (CN)

(72) Inventor: **ChenKang Lin**, Kaonsiung (TW)

(73) Assignee: **Zhuhai Shichang Metals Ltd.**, Zhuhai (CN)

(**) Term: **15 Years**

(21) Appl. No.: **29/585,772**

(22) Filed: **Nov. 29, 2016**

(51) LOC (10) Cl. **06-01**

(52) U.S. Cl.

USPC **D6/716; D6/368**
